UNITED STATES PATENT OFFICE

109,571

DESIGN FOR A RING

Frank L. Thorpe, Deadwood, S. Dak.

Application March 7, 1938, Serial No. 75,650

Term of patent 7 years

To all whom it may concern:

Be it known that Frank L. Thorpe, a citizen of the United States, residing at Deadwood, in the county of Lawrence and State of South Dakota, has invented a new, original, and ornamental Design for a Ring, of which the following is a specification, reference being had to the accompanying drawing, forming part thereof, wherein:

I claim:

The ornamental design for a ring, as shown.

FRANK L. THORPE.
